HOSIERY MENDING DEVICE

August G. Eichholz, St. Louis, Mo., assignor of forty-nine one-hundredths to Albert J. Epelley, St. Louis, Mo., and twentyfour-and-one-half one-hundredths to Joseph Gebhart, St. Louis, Mo.

Application April 14, 1938, Serial No. 202,002

10 Claims. (Cl. 66—1.5)

This invention relates to hosiery mending devices. In hosiery and other knitted fabric, runs are formed by the release of one of the loops. This releases successive loops so that a run of substantial length can form by the straightening of the looped threads.

Among the objects of the invention is the provision of a device having a looping needle extending upwardly and having a support for holding the fabric to be mended in proper position above said needle with the straightened loops or cross threads disposed horizontally and transversely of the hook of said needle, said fabric being movable longitudinally of the run in a direction toward said hook and said needle being operable in a vertical plane progressively to engage and loop the released cross threads.

Another object of the invention is to provide a device comprising a portable stand, means carried by said stand for supporting the fabric in a horizontal taut position, a looping needle operably mounted in said stand for reciprocating movement in a vertical plane past said fabric, successively to engage and loop each transverse thread of a run, and a resilient finger operatively mounted adjacent to the hook end of said needle for closing the hook at each downward movement and releasing the previously looped thread.

Another object of the invention is to provide a reciprocating needle having its upper end terminating in a hook adapted to engage and loop a transverse thread of a run, and a reciprocating member operable in correlation with said needle and provided at its end with a resilient finger for closing the hook of said needle and releasing the looped thread from the shank of said needle, and means for operating said needle and said member in correlation with each other.

Additional objects of the invention are to provide a portable hosiery mending device which is of simple construction and can be manually operated to operate a looping needle and a releasing member in correlation with each other and in a plane at right angle to the plane of the fabric to be mended.

With these and other objects in view, my invention consists in certain novel features of construction and arrangement of parts hereinafter more fully described and claimed, and illustrated in the accompanying drawings, in which—

Figure 1 is a side elevation of my device.

Figure 2 is a front elevation of same.

Figure 3 is an enlarged side view of the upper

end of the needle showing the hook in its uppermost position.

Figure 4 is an enlarged detail cross section of the operating mechanism showing the needle bar in raised position.

Figure 5 is a front elevational view of Figure 3.

Figure 6 is a front elevational view of the parts shown in Figure 4.

Figure 7 is a view similar to Figure 3 but showing the hook end of the needle in lowermost position, and the resilient finger in hook-closing position.

Figure 8 is a view similar to Figure 4 but showing the mechanism in moved position.

Figure 9 is an enlarged detail view, partly in cross section, of the needle bar and the resilient finger bar.

Figure 10 is an enlarged horizontal cross section taken on line 10—10 of Figure 1.

Figure 11 is a horizontal cross section taken on line 11—11 of Figure 4.

Figure 12 is an enlarged detail cross section of the needle bar and the closing member bar.

Referring by numerals to the accompanying drawings, 10 indicates a stand in the form of a cylindrical housing, the lower end 11 of which is removable to provide access to the interior of said housing. Extending upwardly from said housing is an arm 12, the lower end of which is fixed to the housing in any suitable manner. If desired, arm 12 can be formed integral with said housing. This arm is comparatively thin but is of substantial width to obtain the required rigidity.

Revolutely mounted in the upper end of said arm is a horizontally disposed pin 14 and fixed to each end of said pin is a roller support 15. These rollers are spaced apart by the thickness of arm 12 and are therefore in close proximity to each other. Preferably these rollers have their peripheries curved and the outer ends reduced in diameter so that each roller is in the shape of a truncated semisphere. The purpose of these rollers is to provide a support for the stocking to be mended, the run in the stocking being disposed above and in alignment with the space between said rollers.

A vertically disposed needle bar 16 is slidably mounted in a groove 17 formed in one side of arm 12. A plate 18 closes said groove and holds said needle bar in place. This groove extends preferably the full length of said arm and is disposed to one side of pin 14 so that the needle bar clears said pin, as shown in Figure 1. The upper end of bar 16 projects above the upper end of

arm 12 and terminates in a hook 19 presented forwardly to the pin 14. Groove 17 and bar 16 are preferably rectangular in cross section so as to maintain said bar 16 and hook 19 in proper position at all times.

5 This bar 16 is hollow, as indicated at 16a, and is provided with an opening 20 near the upper or hook end 19. Slidably mounted in the groove 16a of bar 16 is a bar 21, the upper end of which has fixed thereto or terminates in a leaf spring finger or resilient member 22. Bars 16 and 21 are movable relatively to each other so that when bar 16 is in a depressed position bar 21 is raised sufficiently to project finger 22 through opening 20 and bring it against said hook 19 so as to close the same.

10 Bars 16 and 21 are actuated, respectively, by cams 25 and 26 which are fixed to a shaft 27 horizontally mounted in bearings 28 of casing 10. One end of this shaft extends outwardly from said casing and can be operated either manually or mechanically. As shown in the drawings, a hand wheel 29 is fixed on said projecting end for manual operation of said shaft.

15 25 The lower ends of bars 16 and 21 extend into said casing 10 and bar 16 is provided with a lateral projection 30 which overlies and rests upon cam 25, while bar 21 is provided with a lateral projection 31 which overlies and rests upon cam 26. A coiled expansion spring 32 is interposed between projection 30 and the top wall of the casing and serves to hold said projection 30 downwardly against the peripheral face of cam 25, thereby urging the needle bar 16 into depressed position. A similar spring 33 bears against the projection 31 and the top wall of said casing and serves to hold said projection against the peripheral face of cam 26 and urge the closure bar 21 into a depressed position.

20 40 Cams 25 and 26 are mounted in a substantially reverse relation to each other so that when one cam occupies raised position the other cam is presented in an opposite direction. Thus when cam 25 has its high point presented upwardly to raise the needle 19 above the peripheries of revoluble supports or rollers 15 and the fabric supported thereon, the high point of cam 26 is presented downwardly (see Figs. 3 and 4).

45 50 When the shaft 27 is actuated to bring the high point of cam 25 downwardly, cam 26 is presented upwardly, as shown in Figure 8. In this position the hook or needle 19 is depressed below the peripheries of the roller supports 15 and the fabric supported thereon and the bar 21 is raised to project the spring member 22 outwardly through opening 20 into engagement with hook 19 and close the same, as shown in Figure 7.

55 60 In using the device the stocking is placed on the support members 15 with the run presented in alignment with the space between said supports and toward the hook 19. The fabric is held taut on said supports with the left hand, while the wheel 29 is turned with the right hand to operate the device. Preferably the bar 16 occupies its uppermost position. In positioning the fabric on the support. The hook 19 is forced through the fabric adjacent to the end of the run through the last loop. The bar 16 is now moved downwardly with the hook 19 engaging and pulling downward said loop. On the upward movement of the bar 16 the loop portion slips over the shank portion of the hook past the opening 20. When the hook 19 again occupies its upward position the supports 15 are slightly turned to bring the first released loop or straight

10 transverse thread under said hook. On the downward movement of bar 16, hook 19 engages said straight portion and pulls it downward. After the hook 19 moves below the fabric bar 21 moves upward and projects the resilient finger 22 through opening 20 into closing engagement with hook 19. The previously looped portion which occupied position on the shank of the hook is released from bar 16 and moves upward to its normal position, thereby being locked by the loop portion held by the hook 19. On the next upward movement of the hook the last-mentioned looped portion is moved over the shank past opening 20 and supports 15 are again turned to bring the next straight thread under the hook 19. The operation is repeated, each straight or released thread portion being successively looped and then released over the next looped portion until the entire run is mended. When the end of the run is reached, where the tear occurred which started the run, the torn portion is repaired with a thread and needle and the last looped portion is engaged by the thread and worked or sewed in to lock said loop and prevent recurrence of the run. Thus the run can be efficiently and quickly repaired. The work is held on the supports 15 by hand and the device is resting on a table or other stationary support. The hook is automatically operated by the manual operation of shaft 27 and as said hook operates upwardly through the fabric, the work can be watched with ease. The looped thread is automatically released from the hook over each succeeding loop and locked by the latter.

15 20 25 The device is portable and light in weight. It can be economically manufactured and is very easy to operate.

30 35 While I have disclosed herein the preferred form of my device, it is to be understood that my invention is not limited to the particular construction herein shown and described, as the same may be variously modified without departing from the spirit of my invention.

I claim:

40 45 50 55 1. A device for mending knitted fabric comprising a portable base, an upward extension thereon, a reciprocating needle bar mounted in said extension for movement in a vertical plane, a hook at the upper end of said bar, a reciprocating release bar mounted in said extension for movement in a vertical plane and operable in correlation with said needle bar, and a resilient finger fixed on the upper end of said release bar and adapted to engage and close said hook.

60 65 70 75 2. A device for mending hosiery comprising a portable stand, an upward extension thereon, a vertically disposed reciprocating needle bar mounted in said extension, a looping hook at the upper end of said bar, a reciprocating release bar mounted in said extension for movement in a vertical plane, a resilient finger fixed on the upper end of said bar and adapted to close said looping hook upon the downward movement thereof, and means in said stand for operating said needle bar and said release bar in correlation with each other.

80 85 90 95 3. A device for mending runs in knitted fabric comprising a hollow portable base, an upward extension fixed thereon, a support mounted on the upper end of said extension for supporting the fabric, said support being formed in two spaced sections, a reciprocating hook needle operatively mounted in said extension and movable upwardly through between said sections for en-

- gaging a transverse straight thread of a run and loop said thread downwardly below the plane of said fabric, and resilient finger operatively mounted in said extension and operable into closing engagement with the hook end of said needle on the downward movement thereof to release the previously looped thread located on the shank of said needle over the looped thread held by said hook. 5
10. A device for mending runs in knitted fabric comprising a hollow portable base, an upward extension fixed thereon, a support mounted on the upper end of said extension for supporting the fabric, said support being formed in two spaced sections, a vertically disposed reciprocating needle operatively mounted in said extension and having a hook on the upper end for engaging a transverse straight thread of said fabric and looping it below said support, a resilient finger operatively mounted in said extension and adapted to engage and close said hook on the downward movement thereof, whereby the previously looped thread positioned on the shank of said needle is released over the looped thread held by said hook, and manually operable means in said base for actuating said needle and said finger. 15
20. A device for mending runs in knitted fabric comprising a portable hollow base, an upward extension on said base, a support mounted on the upper end of said extension, said support being formed in two spaced sections adapted to support the fabric to be mended, a vertically disposed reciprocating needle bar operatively mounted in said extension and projecting into said base and having a hook on the upper end for engaging a transverse straight thread of said fabric and looping it below said support, a resilient finger bar operatively mounted in said extension and extending into said base, a resilient finger fixed on the upper end of said bar, and adapted to engage and close said hook on the downward movement thereof, whereby the previously looped thread positioned on the shank of said needle is released over the looped thread held by said hook, and means in said base for engaging the projecting ends of said bars and actuating said needle and said resilient finger in correlation with each other. 25
30. A device for mending knitted fabric comprising a support for the fabric to be mended, said support being provided with an opening, a vertically disposed reciprocating needle operatively mounted below said support and having a hook on the upper end for engaging a transverse straight thread of said fabric and looping it below said support, a resilient finger operatively mounted below said support and adapted to engage and close said hook on the downward movement thereof, whereby the previously looped thread positioned on the shank of said needle is released over the looped thread held by said hook, means for actuating said needle and said resilient finger in correlation with each other, and a manually operable member for operating said means. 35
35. A device for mending knitted fabric comprising a stationary arm, a pair of horizontally disposed rollers revolvably mounted on said arm in spaced relation with each other and adapted to support said fabric, a needle bar slidably mounted in said arm and having a hook at its upper end, said needle bar being movable in a vertical plane through said fabric, a closure bar slidably mounted in said arm for movement parallel with said needle bar and having a flexible upper end adapted to close the hook of said needle bar and release the previously looped thread from the shank of said hook over the looped thread engaged by said hook, spring means for yieldably forcing each bar downwardly, and manually operable means for actuating each bar upwardly. 40
40. A device for mending knitted fabric comprising a stationary arm, a pair of horizontally disposed rollers revolvably mounted on said arm in spaced relation with each other and adapted to support said fabric, a needle bar slidably mounted in said arm and having a hook at its upper end, said needle bar being movable in a vertical plane through said fabric, a closure bar slidably mounted in said arm for movement parallel with said needle bar and having a flexible upper end adapted to close the hook of said needle bar and release the previously looped thread from the shank of said hook over the looped thread engaged by said hook, and manually operable means for actuating said needle bar and said closure bar in time relation with each other. 45
45. A device for mending knitted fabric comprising a pair of spaced-apart rollers for supporting the fabric to be mended, a vertically disposed reciprocating needle operatively mounted below said rollers and having a hook on its upper end for operating between said rollers engaging a transverse straight thread of said fabric and looping it below the peripheries of said rollers, a resilient finger operatively mounted between said rollers and below the periphery thereof and adapted to engage and close said hook on the downward movement thereof to allow the previously looped thread to be released from said needle, and manually operable means for actuating said needle and said resilient finger. 50
50. A device for mending knitted fabric comprising a pair of rollers for supporting said fabric, a vertically disposed reciprocating needle operatively mounted below said rollers and having a hook on its upper end for engaging a transverse straight thread of said fabric and looping it below the peripheries of said rollers, a resilient finger operatively mounted between said rollers and below the periphery thereof and adapted to engage and close said hook on the downward movement thereof to allow the previously looped thread to be released from said needle, means for actuating said needle and said resilient finger in correlation with each other, and a manually operable shaft for operating said means. 55
55. A device for mending knitted fabric comprising a stationary arm, a pair of horizontally disposed rollers revolvably mounted on said arm in spaced relation with each other and adapted to support said fabric, a needle bar slidably mounted in said arm and having a hook at its upper end, said needle bar being movable in a vertical plane through said fabric, a closure bar slidably mounted in said arm for movement parallel with said needle bar and having a flexible upper end adapted to close the hook of said needle bar and release the previously looped thread from the shank of said hook over the looped thread engaged by said hook, spring means for yieldably forcing each bar downwardly, and manually operable means for actuating each bar upwardly. 60
60. A device for mending knitted fabric comprising a stationary arm, a pair of horizontally disposed rollers revolvably mounted on said arm in spaced relation with each other and adapted to support said fabric, a needle bar slidably mounted in said arm and having a hook at its upper end, said needle bar being movable in a vertical plane through said fabric, a closure bar slidably mounted in said arm for movement parallel with said needle bar and having a flexible upper end adapted to close the hook of said needle bar and release the previously looped thread from the shank of said hook over the looped thread engaged by said hook, and manually operable means for actuating said needle bar and said closure bar in time relation with each other. 65

AUGUST G. EICHHOLZ.
